2,344,455

CHAIN

Sidney J. Bertheman, Chepachet, R. I., assignor
to L. & B. Jewelry Manufacturing Company, a
corporation of Rhode Island

Application April 14, 1942, Serial No. 438,866

2 Claims. (Cl. 59—80)

This invention relates to a chain, more particularly for use as an article of jewelry such as a bracelet band, belt, or the like. More specifically the invention relates to the lazy tong arrangement of links and the particular means for connecting these links one to the other.

Heretofore in the connection of links in the lazy tong arrangement one to the other, rivets have been used which are expensive for assembly, or some hook arrangement has been used which may become accidentally detached and permit the bracelet band, belt or the like, to become completely disconnected.

One of the objects of this invention is to provide an inexpensive connection between the links of a bracelet of the above mentioned type which will require a minimum expenditure of time and material for construction and which may be easily and quickly assembled.

Another object of this invention is to provide a construction which when assembled cannot be accidentally detached one unit from the other.

With these and other objects in view, the invention consists of certain novel features of construction, as will be more fully described and particularly pointed out in the appended claims.

In the accompanying drawing:

Fig. 1 is a top plan view illustrating the linkage which is the subject of this invention.

Fig. 2 is a view of the linkage in expanded relation, with parts removed, and other parts in section, to illustrate the construction of the chain.

Fig. 3 is a perspective view of one of the links shown prior to final formation.

Fig. 4 is a perspective view of the link with a T-headed stud bent into finished position.

Fig. 5 is a perspective view of the other link, with the tongues at the ends of the opening in raised position.

Fig. 6 is a fragmental perspective view on a large scale illustrating one of the T-shaped studs extending through an opening with the tongue portion bent into locking position.

Fig. 7 is a bottom perspective view of a cover member for one of the links.

The chain which I provide consists of essentially three parts; a link designated generally 10, a companion link of the shape shown generally in Fig. 5 and designated 11, and a cover member shown in inverted form in Fig. 7 and designated generally 12 which fits over the link 10 and hides the working parts of the assembly.

The link 10 is cut out of sheet stock as shown in Fig. 3 with studs 14 formed at either end thereof and in the same plane as the body of

5 the link, while at the center of the link a tubular portion or rivet 15 is provided, either as a separate part or drawn up from the stock of the body of the link. The studs are bent from the position shown in Fig. 3 through substantially 90 degrees, to the position shown in Fig. 4, each stud comprising a neck portion 16 and a T-shaped head 17 at the free end thereof. A recess 27 is formed in the opposite face of the link to receive one arm of a spring as will hereafter appear.

10 The link 11 consists of a body portion with elongated slots 18 at either end thereof, which consist of circular portions 19 and a portion 20 extending inwardly from the circular portions by reason of a tongue 21 being cut and bent back to form these elongated slots as shown in Fig. 5. A bearing opening 22 is provided at the center of the link to receive and pivot upon the tubular portion 15 of the link 10, while lugs 23 are raised at the edge of the link to serve to retain the end of the spring 24 which tends to swing the links one relative to the other.

15 In assembly, a link 11 is pivotally mounted upon a link 10 by positioning the opening 22 over the central tubular portion 15 which is then spun as at 26 to provide a headed portion to limit the lateral play of the links 11 and 10. Each unit so arranged is then connected to another similar 20 unit by the T-headed studs 14 being passed through the elongated openings 18 and after the studs have been passed through these openings, the tongues 21 are bent from the position shown in Fig. 5 to the position shown in Fig. 6, to close the portion 20 of the elongated openings 18 and leave only the circular portions 19 thereof extending about the necks 16 of the studs so as to pivotally relate the units comprising links 10 and 11 as shown in Fig. 2. A spring 24 is assembled 25 within the tubular portion or hollow rivet 15 with one end located in a recess 27 in the under side of the link 10 as shown in Fig. 2 while the other end extends beneath the retaining lug 23 on the link 11, there being sufficient tension in the spring 30 so as to tend to move the arm which engages the lug 23 in one direction, and move the arm which engages the recess 27 in the opposite direction, causing the links of each unit to swing about their pivot into contracted position.

35 A cover is assembled upon the link 10 so as to conceal the spring and the T-headed stud and thus provide a chain of more ornamental appearance. This cover is shaped to conform substantially to the shape of the link 10 having a top wall 29 and a flange 30, the flange being rolled

beneath the edge of the body of the link 10 to hold it in position.

The use of a T-headed stud provides a very secure lock and yet a pivotal arrangement which is very satisfactory, and by lifting some of the stock from a point adjacent the opening in which the stud is pivoted I then may put the large head through this opening and by moving the stock back into position from which it was lifted I lock the head securely against accidental detachment. A very strong and durable structure is thus provided in a lazy tong arrangement of links to provide a chain for use as a jewelry article.

I claim:

1. In a linkage of units for articles of personal wear, each unit comprising a pair of sheet stock links arranged in parallel planes one above the other and pivoted together at their centers to move one relative to another each in its own plane, one of said links being provided with T-headed studs extending upwardly at right angles to the general plane of the link, the other of said links having openings inwardly from the edge of the link of a size to receive said T-headed studs therethrough, and a tongue movable from and into a portion of said opening, said units being connected together by the T-headed studs of one

unit passing through the openings in the link of the next unit to pivotally connect the units and links in lazy tong relation, the T-heads of said studs being blocked from disengagement by said tongues in said openings.

2. In a linkage of units for articles of personal wear, each unit comprising a pair of sheet stock links arranged in parallel planes one above the other and pivoted together at their centers to move one relative to another each in its own plane, one of said links being provided with T-headed studs folded from an edge of the link into a position at right angles to the general plane of the link, the other of said links having openings inwardly from the edge of the link of a size to receive said T-headed studs therethrough, and a tongue movable from and into a portion of said opening, said units being connected together by the T-headed studs of one unit passing through the openings in the link of the next unit to pivotally connect the units and links in lazy tong relation, the T-heads of said studs being blocked from disengagement by said tongues in said openings so positioned that pivoting about said studs causes said heads to swing over said tongues.

SIDNEY J. BERTHERMAN.
